UNITED STATES PATENT OFFICE.

EZEKIEL HOLMAN, OF SANDY, UTAH TERRITORY.

COMBINED ROASTING AND SMELTING FURNACE.

SPECIFICATION forming part of Letters Patent No. 286,822, dated October 16, 1883.

Application filed July 16, 1883. (No model.)

To all whom it may concern:

Be it known that I, EZEKIEL HOLMAN, of Sandy, in the county of Salt Lake and Territory of Utah, have invented a new and useful Improvement in Roasting and Smelting Furnaces, of which the following is a full, clear, and exact description, reference being had to the annexed drawings, forming part of this specification.

10 This invention relates to combined roasting and smelting furnaces for the reduction of silver, lead, and other ores; and the invention consists of the novel construction hereinafter described and claimed.

15 In the drawings, Figure 1 is a side elevation of my improved roasting and smelting furnace. Fig. 2 is a longitudinal section of the same; and Fig. 3 is a cross-section on line $x x$ of Fig. 1, enlarged.

20 A indicates the fire-chamber, B the fire-grate, and C the ash-pit, of the furnace. From the bridge-wall D, at the rear of the fire-chamber, extends a flue, E, which inclines slightly upward from the fire-chamber and terminates 25 at the base of the chimney F, with which it communicates. The chimney and flue are provided with a continuous partition, which is supported on parallel vertical walls H in the bottom of the flue, forming an inclined floor 30 or hearth, G, and a series of under flues, I, in order that the hot air shall completely envelop the ores as they are fed down the hearth G from the feed-door J at the base of the chimney. The inclined hearth leads to the smelting-cavity K, in which the melted ore is collected.

35 L M are holes leading to the well, for extracting the metal and slag.

40 N indicates a series of small doors in the sides of the inclined flue E, through which the

progress of the ore to the bottom or smelting-cavity may be noticed and aided when necessary.

K' is the lead-well, partly broken away, and K² K³ are weighted doors, and K³ is a platform 45 by which the doors N are reached.

In the upper part of the furnace-walls is located a superheater, O, which is to be supplied with steam by the pipe P, and which in turn supplies steam to the superheater Q, at the 50 top of the fire-chamber, by means of the pipe R. Superheated steam is to be jetted into the fire-chamber from the superheater Q through an opening, S. Through the roof of the furnace enters a blast-pipe, T, which is adapted 55 to direct the blast in such manner as to keep the roof from being burned out by the heat from the fire-chamber, and which forces the hot air directly on the ore, where it falls to the bottom of the flue E from the hearth G. 60

With the above construction coke and other high priced fuels may be dispensed with, as ordinary coal can be used with good results.

What I claim is—

1. The combined roasting and smelting furnace having the inclined hot-air flue E, provided with the roasting-hearth G, under flues I, and side doors, N, and the smelting-cavity K, substantially as shown and described. 65

2. The combination of the inclined hot-air 70 flue E, having the inclined hearth G and smelting-cavity K, the fire-chamber A, the superheater Q, and blast-pipe T, adapted to force the hot-air on the ore as it falls from the hearth G, substantially as shown and described.

EZEKIEL HOLMAN.
